H. O. McMILLAN

CLAMPING DEVICE FOR CONCRETE FORMS

Filed July 12, 1924

INVENTOR.
HOWARD O. McMILLAN.
BY HIS ATTORNEY.

James F. Williamson

UNITED STATES PATENT OFFICE.

HOWARD O. McMILLAN, OF MINNEAPOLIS, MINNESOTA.

CLAMPING DEVICE FOR CONCRETE FORMS.

Application filed July 12, 1924. Serial No. 725,712.

To all whom it may concern:

Be it known that I, HOWARD O. McMILLAN, a citizen of the United States, residing at Minneapolis, in the county of Hennepin 5 and State of Minnesota, have invented certain new and useful Improvements in Clamping Devices for Concrete Forms; and I do hereby declare the following to be a full, clear, and exact description of the invention, such as will enable others skilled in the art to which it appertains to make and use the same.

This invention relates to a clamping means and particularly to such a means 15 adapted to be used to hold concrete forms or other building structure of various kinds in fixed position. The clamp is especially adapted for use where the parts are held together by parallel wires or rods extending 20 therealong, and engaging a tightening means. Such tightening means, as illustrated, comprises a spindle to the ends of which the wires or rods are secured, said spindle then being rotated to tension the 25 wires or rods and then held in position with said wires or rods tight or under tension.

It is an object of this invention to provide such a clamping means comprising a spindle having end portions provided with apertures 30 adapted to receive wires or rods, together with clamping means for holding said wires or rods securely in said end portion.

It is also an object of the invention to provide such a spindle having end portions apertured to receive the wires or rods, said spindle having clamping screws in the ends thereof adapted to engage the wires in said 40 apertures to hold the same during the tightening operation and after the same are tightened.

It is further an object of the invention to provide a spindle as above set forth, in which the clamping screws extend into the 45 ends of the spindle and longitudinally thereof.

It is more specifically an object of the invention to provide such a spindle having a central portion adapted to be rotated and 50 having means for holding it in various rotated positions and having end portions provided with transverse apertures, said end portions also having clamping screws extending substantially axially thereinto and 55 said apertures having spaced transverse raised portions at each side of said clamp-

ing screws whereby the wire extending through said aperture will be pressed between said raised portions by said clamping screws and securely held in position. 60

These and other objects and advantages of the invention will be fully set forth in the following description made in connection with the accompanying drawings in which like reference characters refer to the same 65 parts throughout the different views, and in which,

Fig. 1 is a perspective view showing the device in position clamping the parts of the concrete form together; 70

Fig. 2 is a vertical section taken substantially on the line 2—2 of Fig. 1;

Fig. 3 is a view in side elevation of the end portion of the spindle used; and

Fig. 4 is a vertical section taken on the 75 line 4—4 of Fig. 3, as indicated by the arrows, Figs. 2, 3 and 4 being shown on an enlarged scale.

Referring to the drawings, a form for a concrete wall is illustrated comprising the 80 vertical posts 1 and 2, the side boards 4 and a spacing strut 3 shown as extending between the top boards 4. While the invention is shown as applied to a form for a wall it is, of course, obvious that it will be applied to clamp or hold together any desired 85 members.

In the embodiment of the invention illustrated, the form, and particularly the posts 1 and 2 are embraced by the wire 5, the ends 90 of which are secured to and wound about a spindle member 6 which engages the outer side of the post 2. The spindle 6 is provided with angularly spaced slots 6^a adapted to receive a key member 7. The key member 7 is shown as formed of a flat bar bent substantially at right angles and having a short arm 7^a and a longer arm 7^b.

In order to hold the ends of the wire 5 securely in the spindle 6 during the tightening operation, said spindle is provided with end portions adapted to project beyond the post 2, each of which has extending therethrough an aperture 6^b. While the aperture 6^b may be of various forms, in the embodiment of the invention illustrated, the same is shown as being substantially cylindrical. The end portions of the spindle are also provided with a bore extending longitudinally thereof which is threaded to receive a 105 clamping screw 8 illustrated as in the form of an ordinary set screw and which, prefer-

ably, extends substantially axially of the spindle 6. The aperture 6^b is provided on its inner side with raised portions 6^c spaced at either side of the set screw 8 and illustrated as being in the form of sharp-edged ribs.

In operation, the wires or light rods 5 will have their ends inserted through the apertures 6^b and drawn substantially into tight position. The set screw 8 will then be tightened and the same will press against the said wire and tightly clamp the same, said wire being depressed between the projections 6^c, as shown in Fig. 4. The set screw 8 will also tightly engage and bite into the wire so that the wire is very securely held in position in the end of the spindle. The spindle is now turned by inserting a bar into the slot 6 until the parts are sufficiently clamped and the desired tension placed upon the wires or rods 5. When the wires are thus sufficiently tightened the key 7 is inserted in one of the slots 6^a so as to engage the outer side of post 2 and prevent backward rotation of the spindle 6. By providing the long and short arms on the key 7, and having the angularly disposed slots 6^a, the key can be placed in sixteen different positions so that a very slight, if any, retrograde movement of the spindle 6 is permitted. It will be noted, as shown in Fig. 2, that the key can be placed in reverse positions in the slots 6^a. The tightening wire or rod is thus quickly brought to the desired tension and securely held in position. When it is desired to loosen the parts, the key 7 will be removed and the wires or clamping rods slackened, or the set screws 8 can quickly be loosened to permit slackness of said wires.

From the above description it is seen that applicant has provided a very simple and efficient clamping device and one which has a high degree of utility in clamping concrete forms, shoring timbers etc. The clamp can quickly and easily be brought to clamping position and can be quickly released and also holds the clamped parts securely in position. The device is easily and quickly made and can be produced at a low cost.

The device has been amply demonstrated in actual practice and found to be very successful and efficient.

It will, of course, be understood, that various changes may be made in the form, details, arrangement and proportions of the parts without departing from the scope of applicant's invention which, generally stated, consists in a device capable of carrying out the objects above set forth, such as shown and described and defined in the appended claims.

What is claimed is:

1. A clamp of the class described comprising a spindle having an intermediate portion adapted to engage a support, said spindle having end portions apertured to have a wire or rod pass therethrough, and a set screw threaded into each end of said spindle and extending longitudinally thereof adapted to engage said wires or rods in said apertures and clamp the same in position.

2. A clamp of the kind described comprising a spindle having an intermediate portion adapted to engage an abutment, said spindle having end portions, each end portion having a transverse aperture therethrough adapted to receive a rod, a clamping screw extending substantially axially into the outer end of said portion, said spindle having spaced raised portions extending transversely of said aperture at each side of said screw, said screw being adapted to press a wire or rod between said raised portions and clamp the same securely in position.

3. The structure set forth in claim 2, said raised portion comprising sharp edged ribs.

4. A clamp of the kind described comprising a rotatable spindle having an intermediate portion adapted to engage and be rotated relatively to a support, said spindle having end portions with transverse apertures extending therethrough adapted to receive rods, and means carried by said spindle and threaded thereinto extending into said apertures to engage and clamp said rods rigidly therein, and means for holding said spindle in various rotated positions.

In testimony whereof I affix my signature.
HOWARD O. McMILLAN.
